UNITED STATES PATENT OFFICE.

HERMAN HENTSCHKE AND JOHN BROWN, OF COUNCIL BLUFFS, IOWA.

BOTTLE-STOPPER.

SPECIFICATION forming part of Letters Patent No. 351,769, dated November 2, 1886.

Application filed July 26, 1886. Serial No. 209,124. (No model.)

To all whom it may concern:

Be it known that we, HERMAN HENTSCHKE and JOHN BROWN, citizens of the United States, residing at Council Bluffs, in the county of 5 Pottawattamie and State of Iowa, have invented a new and useful Improvement in Bottle-Stoppers, of which the following is a specification.

Our invention relates to an improvement in 10 bottle-stoppers; and it consists in the peculiar construction and combination of devices, that will be more fully set forth hereinafter, and particularly pointed out in the claims.

In the drawings, Figure 1 is a perspective 15 view of a bottle-stopper embodying our improvements. Fig. 2 is a side elevation of the same. Fig. 3 is a vertical sectional view. Fig. 4 is a horizontal section on line $\alpha\alpha$ of Fig. 3. Fig. 5 is a top plan view. Fig. 6 is a top plan 20 view with the lid removed.

A represents the neck of a bottle or jar, which is provided on opposite sides, near its upper end, with projecting tenons B, which are blown with the bottle or jar.

25 C represents a collar, which is made of india-rubber or other suitable elastic material, and the said collar is provided on opposite sides with openings which correspond with the tenons B, and at the upper edge of the collar is 30 an annular flange or shoulder, C'. This collar is stretched over the upper portion of the neck of the bottle or jar, and is secured firmly thereto by passing the tenons through the openings thereof.

35 D represents a metallic collar, which is made in two sections, hinged together by means of the pivotal pins E, which extend vertically through projecting intermeshing tongues D', with which the sections of the collar are provided. The 40 said sections of the collar are provided at right angles to the hinged joint with openings D'', adapted to receive the projecting outer ends of the tenons B. The said collar is placed around the upper portion of the neck of the 45 bottle or jar, and compresses the rubber collar C, as shown. From the lower side of one section of the collar project outwardly-extending lugs d, between which is hinged or pivoted the lower end of a catch, F, and from the opposite side of the other section of the collar, at the upper edge thereof, project ears or lugs d', between which is hinged a lid or cover, G.

50 The said lid or cover is provided on its under side with a depending annular flange, g, which is adapted to enter the recess formed between

the collar D and the neck of the bottle or jar, above the upper edge of the rubber collar C, and when the said lid or cover is closed on the top of the bottle or jar the said flange g bears down firmly upon the upper edge of the rubber collar and forms an air and water tight joint. From the free side of the lid or cover projects a pair of ears, g', the outer ends of which are inclined or beveled on their upper sides, and in rear of the said inclines are made 60 depressions g''. The catch F is provided at its free ends with a T-shaped head, f. When the lid or cover is closed, the catch F is swung outwardly, and the upper portion of the shank of the said catch enters between the projecting lugs g' of the lid or cover, and the head of the catch is guided over the said lug by means of the inclines and the tongue seated in the 65 depressions g'', thereby firmly locking the lid or cover when closed.

A bottle or jar stopper thus constructed is 70 cheap and simple, is very efficient and strong and durable, and is very easily operated.

Having thus described our invention, we 75 claim—

1. The combination, with the bottle or jar having its neck provided with the projecting tenons, of the elastic collar fitted on the neck of the bottle or jar, and having the openings to receive the tenons, and the collar D, fitted 80 over the elastic collar, and also provided with openings to receive the projecting ends of the tenons, the hinged cover, and the catch secured to the collar D, to lock the cover when closed, substantially as described.

2. The elastic collar C, fitted to the neck of a bottle or jar, and the metallic collar D, fitted around the elastic collar and having its upper edge extended above the upper edge of the elastic collar, and the cover G, having its 85 outer edge resting flat on the upper edge of the metallic collar, and a flange, g, depending from the cover, and adapted to fit in the space between the neck of the bottle and the metallic collar and rest upon the elastic collar, as 90 set forth.

In testimony that we claim the foregoing as our own we have hereto affixed our signatures in presence of two witnesses.

HERMAN HENTSCHKE.
JOHN BROWN.
